UNITED STATES PATENT OFFICE.

CHARLES F. HUMMEL, OF ILION, AND WILLIAM L. PETERS, OF HERKIMER, NEW YORK.

TOP.

Application filed April 3, 1928. Serial No 267,028.

Our invention relates to improvements in detonating toys and more especially to spinning tops, although not necessarily restricted to this use.

5 An important object of our invention is to provide a toy adapted to carry a detonating cap to be exploded when an impact is imparted by the use of the toy.

10 A further object of our invention is the provision of a spinning top which will explode a cap when used, and which will have a spring pressed point adapted to impart a bounding and rebounding movement to the top.

15 Other objects and advantages of our invention will be apparent during the course of the following description.

20 In the accompanying drawings which form a part of this specification and wherein like characters of reference denote like or corresponding parts throughout the same,

Figure 1 is a side elevation of a top embodying our invention,

Figure 2 is a central longitudinal sectional view therethrough,

Figure 3 is a top plan view thereof,

Figure 4 is a detail view of the cap disk and its associated cylinder, and

Figure 5 is a detail view of a modified 30 form of plate.

In the drawings, wherein for the purpose of illustration is shown a preferred embodiment of our invention, the numeral 10 designates the tapering body of the top which is provided with a central longitudinal bore adapted to snugly receive a central core or cylinder 11 which projects beyond the tapered lower end of the top body and is provided with a circumferential groove 12 immediately below the lower end of the body

40 of the top to facilitate the application of a cord or other spinning member. The lower end of the core or cylinder 11 tapers to a centrally arranged bore 13 which extends longitudinally through the cylinder

45 and opens into an elongated well or hollowed out portion 14 at the upper end of the cylinder. The cylinder 11 extends above the top body and is provided with a cover 15 which closes the upper end of the well 14. The cylinder is cut away laterally between the top body and the cover 15 to form diametrically opposed openings 16 separated by rib sections 17, the openings 16 extending

55 up to the cover 15.

A plate 18 is provided with a pair of arcuate slots 19 adapted to slidably receive the rib sections 17 whereby the plate is free to slide the entire length of the slots 16 in a vertical direction, the plate extending 60 through the well 14 and beyond the cylinder 11 on all sides.

A spindle 20 is slidably arranged in the bore 13 and has its lower end pointed and normally projecting below the tapered end 65 of the cylinder 11. The upper end of the spindle terminates a short distance below the plate 18, and a disk 21 is rigidly secured to the spindle at a point spaced from the upper end thereof, said disk being normally 70 pressed against the bottom of the well by a coil spring 22 which presses against the disk at one end and the plate at its other end, the spring being arranged around the upper end of the spindle.

75 In operation the plate 18 is forced downwardly against the tension of the spring 22 and a detonating cap 23 is arranged between the plate 18 and the cover 15, and is retained in place by the tension of the spring 80 80 forcing the plate 18 upwardly. The operation of the plate is facilitated by its edges being projected beyond the walls of the cylinder.

When the top is spun, the impact on the 85 lower end of the spindle will drive the entire spindle upwardly against the tension of the spring 22 and cause the upper end of the spindle to strike the plate 18 and explode the cap. The spring 22 will tend to 90 force the spindle back to its normal position shown in Figure 2, with the result that a bounding and rebounding movement will be imparted to the top.

In Figure 5 I have illustrated a slight 95 modification in which the plate 18 is provided with an aperture 24 to allow passage of the upper end of the spindle. In this form of my invention the cap is exploded by the direct impact of the spindle.

100 Although we have illustrated our invention as applied to a top, we contemplate its application to other toys such as a toy arrow. It will be seen from Figure 2 that a toy arrow could be formed by leaving off 105 the top body and modifying the proportions of the cylinder 11 and its associated elements, the cap being exploded by the impact of the arrow against its target.

110 While we have shown and described the

preferred embodiment of our invention, it is to be understood that various changes in the size, shape and arrangement of parts may be resorted to without departing from the spirit of our invention or the scope of the subjoined claims.

Having thus described our invention, what we claim and desire to protect by Letters Patent is:

- 10 1. A toy comprising a body having a well therein, said well being closed at its end, said body having a longitudinal bore opening into the well, a spindle slidably arranged in said longitudinal bore, means to support a percussion cap adjacent the closed end of said well, and resilient means normally forcing said spindle away from said cap.
- 15 2. A detonating toy comprising a body having a well therein, said well being closed at one end, said body having a longitudinal bore, a spindle slidably arranged in said bore and extending into said well, a projection on said spindle and spaced from the end of said spindle, a plate slidably arranged in said well adjacent the closed end thereof, and resilient means normally forcing said plate toward the closed end of the well and normally forcing the projection on said spindle to normally force said spindle away from the plate.
- 20 3. A detonating toy comprising a body having a well therein, said well being closed at one end, there being lateral slots in the walls of said well adjacent the closed end thereof, a plate arranged in said well and having portions projecting through said slots, said body having a longitudinal bore, a spindle arranged in said bore and projecting at one end beyond the body and having its other end extending into the well, a lateral projection on said spindle within the

well, and resilient means arranged between said plate and said lateral projection and normally forcing said plate toward the closed end of the well and normally forcing said spindle away from said plate.

4. A detonating top comprising a body portion, a core arranged centrally of said body portion and projecting thereabove, said core having a well in the upper end thereof, the upper end of the well being closed, said core having a centrally arranged longitudinal bore, a spindle arranged in said bore and projecting below the body portion and core and extending into said well, a plate slidably arranged in said well adjacent the closed end thereof, and resilient means normally forcing said plate upwardly toward the closed end of the well, and normally forcing said spindle away from said plate.

5. A detonating top comprising a body portion, a centrally arranged core therein and projecting thereabove, said core having a well in the upper end thereof having its upper end closed, said core having a longitudinal bore therein and having slots provided in the walls of the well above the body portion, a plate arranged in the upper end of the well and having lateral portions extending through the slots and beyond the core, a spindle arranged in said bore and projecting below said body portion and core and having its upper end projecting into the well and spaced from the plate, a disk on said spindle, and a coil spring surrounding the upper end of said spindle and pressing against the plate at its upper end and the disk at its lower end.

In testimony whereof we affix our signatures.

CHARLES F. HUMMEL.
WILLIAM L. PETERS.
